COMBINED LIGHT EMITTING GAS DISCHARGE
MATRIX DISPLAY PANEL AND CONNECTING
CABLES

Larry J. Schmersal and Gerald E. Wojcik, Toledo, Ohio,
assignors to Owens-Illinois, Inc.

Filed Apr. 23, 1971, Ser. No. 137,097

Term of patent 14 years

Int. Cl. D14—02

U.S. Cl. D26—5

FIG. 1

FIG. 2

FIG. 1 is a front elevational view of a combined light emitting gas discharge matrix display panel and connecting cables embodying our new design, the rear being identical to the front shown, as view turned 90 degrees; and

FIG. 2 is a top plan view thereof, the bottom being the same as the top shown.

We claim:

The ornamental design for combined light emitting gas discharge matrix display panel and connecting cables, as shown and described.
